10 invention of Diana P. Williams, Boston, Mass.,
15 assigned to the Corset Company, Boston, Mass.,
20 for a hose supporter. The application was filed
25 on November 27, 1936, Serial No. 112,930.
30

35 This invention relates to hose supporters of
40 the type comprising an upper non-elastic section
45 adapted to be sewed to the corset or other
50 supporting garment, a lower hose-gripping section
55 and an intermediate section of elastic material
60 connecting the upper section and the hose-
65 gripping section.

70 One of the objects of the invention is to provide
75 an improved hose supporter of this type in
80 which the elastic section is a two-ply section
85 throughout its entire length and can be quickly
90 and easily detached from the non-elastic section
95 by simply manipulating a buckle, and can be
100 as quickly and readily connected to said non-
105 elastic section.

110 Other objects of the invention are to improve
115 hose supporters in various other ways as will be
120 more fully hereinafter set forth.

125 In the drawing wherein I have illustrated a
130 selected embodiment of the invention;

135 Fig. 1 is a perspective view of a hose supporter
140 embodying the invention;

145 Fig. 2 is a perspective view showing the manner
150 in which the elastic section is attached to or
155 detached from the non-elastic section;

160 Fig. 3 is an enlarged section through the
165 buckle;

170 Fig. 4 is a view of the buckle;

175 Fig. 5 is a view of the metal loop connecting
180 the non-elastic section to the elastic section.

185 In the drawing 1 indicates the non-elastic
190 section which may be of cloth or tape or non-
195 elastic webbing and which is intended to be
200 sewed permanently to the corset or other sup-
205 porting garment, 2 indicates the hose-support-
210 ing member which may have any suitable or
215 usual construction and is adapted to have the
220 gripping engagement with the hose, and 3 is the
225 intermediate elastic section connecting the non-
230 elastic section 1 with the hose-supporting mem-
235 ber 2. The non-elastic section 1 carries at its
240 lower end a metal loop 4 which is permanently
245 secured thereto. This non-elastic section may
250 be a length of non-elastic fabric which is looped
255 through the metal loop or connecting member
260 4 and which has the two plies or layers thereof
265 sewed together by suitable stitching as indicated
270 at 5.

275 The elastic section 3 is made of a strip 6 of
280 elastic webbing which has a buckle 7 secured
285 thereto at one end.

290 The hose-gripping member 2 is provided at its
295 upper end with a metal loop 8 adapted to receive
300 the elastic webbing 6. This length of elastic
305 webbing 6 is threaded through the loop 8 and

310 through the loop 4 as shown in Fig. 2, after
315 which the free end 9 of the elastic web is in-
320 serted through the buckle 7 and gripped thereby
325 as shown at Fig. 1. This produces an elastic
330 section 3 in the form of an elongated loop hav-
335 ing the two sides 11 and 12 and which is con-
340 nected to the two metal loops 4 and 8 and which
345 can be adjusted as to its length by means of the
350 buckle 7. The elastic section 3 is, therefore, a
355 two-ply section throughout its entire length, and
360 this is an advantage because the tension or
365 strain to which the hose supporter is subjected
370 will be divided evenly between the two sides 11
375 and 12 of the double elastic section so that no
380 portion thereof is required to resist the entire
385 strain to which the hose supporter may be sub-
390 jected. The buckle 7 is shown as having a body
395 portion 13 formed with a slot 14 through which
400 the webbing is adapted to pass and is also pro-
405 vided with a gripping member 15 pivoted to the
410 upper end of the body 13 as shown at 16, said
415 gripping member having the usual thumb-piece
420 17 by which it may be swung into or out of its
425 gripping position shown in full lines Fig. 3. The
430 body 13 of the buckle has fingers 18 struck up
435 therefrom, said fingers being directed toward
440 the slot 14. The buckle is secured to the end
445 10 of the elastic webbing by inserting the ex-
450 tremity 19 of the webbing between the fingers
455 18 and the body 13, and then pressing said fin-
460 gers toward the body with the result that the
465 webbing will be crowded into the open spaces
470 20 from which the fingers 18 were struck up.
475 The webbing then is folded over the end of the
480 fingers 18 as shown at 21 thereby forming a per-
485 manent attachment between the webbing and the
490 buckle.

495 I prefer to so assemble the elastic webbing 6
500 with the metal loops 4 and 8 that when the ends
505 9 and 10 of the webbing are buckled together
510 the gripping member 15 and thumb-piece 14 of
515 the buckle 7 and the free end 9 of the elastic
520 webbing will be on the inside of the loop of elas-
525 tic webbing as shown in Fig. 1. With this ar-
530 rangement the outside of the loop will present
535 a smooth surface free from any sharp corners or
540 edges which might cause discomfort to the
545 wearer.

550 An advantage of the construction herein shown
555 is that if at any time the elastic portion needs
560 to be replaced this can be readily accomplished
565 by simply releasing the buckle 7 and withdraw-
570 ing the elastic webbing 6 from the loops 8 and
575 4, and then replacing the discarded elastic web-
580 bing with a fresh webbing by simply threading
585 55

the new webbing through the loops **8** and **4** and buckling the ends together.

Or, if the entire hose supporter as shown in Fig. 1 is sold as a separate unit, a person who has one of these supporters attached to her corset can easily replace the elastic portion, if this becomes necessary, by releasing the buckle **7** and withdrawing the elastic webbing from the loop **4**, which is permanently attached to the corset through the non-elastic section **1**, and then discarding the non-elastic section **1** of the new hose supporter and attaching the elastic section to the loop **4** which is attached to the corset as shown in the drawing.

15 I claim:

A hose supporter comprising a non-elastic

upper section adapted to be sewed to a corset or other supporting garment, a metal loop permanently secured to said upper non-elastic portion, a hose-gripping member having at its upper end a second metal loop, a length of elastic webbing extending loosely through and being detachable from both metal loops, and a buckle separate from each metal loop and secured to one end of the webbing, said buckle having a slot through which the other end of the webbing extends, and a gripping member for gripping the latter end of the webbing, said gripping member being located on the inside of the webbing and the outer face of the buckle below the slot being covered by the webbing.

DIANA P. WILLIAMS.
